UNITED STATES PATENT OFFICE.

FRANCIS H. ROOT, OF BUFFALO, NEW YORK, ASSIGNOR TO JEWETT & ROOT.

DESIGN FOR A COOKING-STOVE.

Specification forming part of Design No. 5,933, dated June 11, 1872.

SPECIFICATION.

I, FRANCIS H. ROOT, of the city of Buffalo, in the county of Erie and State of New York, have invented and produced a new and original Design for Stoves, of which the following is a specification:

My invention relates to a design for the form or configuration and ornamentation of a stove. My invention consists in the design of projecting pillars or columns at the corners of the stove; also in the design of a central raised polygonal figure on the depressed main body of the side and rear plate, (the rear plate is not shown, but is the same in design as the side plates,) and door of a stove; and lastly, in the ornamentation of the side and rear plates, (same as side plates,) door, and legs of the stove with stars in relief, as hereinafter shown and described. My invention is fully shown in the accompanying photographic illustration, representing a perspective view of the stove, to which reference is here made.

A is the top, B the bottom-plate, C the sides, D the door, and E the legs, of the stove. The front, rear, and side plates are so shaped that the corners formed by their junction represent outwardly-projecting pillars or columns F, of semi-polygonal or other suitable form in cross-section. These pillars are provided with appropriate capitals, f, fitting under the projecting corners of the top plate A, and base-moldings f' resting on the projecting corners of the bottom plate B. The capitals of the corner-pillars F are connected by cornices g, and their bases f' by moldings g', of the style shown, forming an appropriate connection between the projecting edges of the top and bottom

plates and the more inwardly-arranged vertical plates of the stove. The side and rear plates and the door D are embellished each with a polygonal figure, h, cast in bass-relief and arranged centrally on those parts. The faces of these polygonal figures are made to slightly rise toward the center. The center of each of these figures is ornamented with a large star or sun, i, formed by ribbed rays applied in relief, while stars of various sizes are arranged around this central star on the raised surface of said polygonal figures. The legs E are also ornamented each with one or more stars. The figure of a star is the characteristic feature of the ornamentation of this stove. The word "star" is applied in raised letters to the top plate, and designates the name or denomination of this kind of stove.

I claim as my invention—

1. The design of pillared corners for a stove, as shown and described.
2. The design of the cornices at the junction of the side and end plates with the top and bottom plates of a stove, as shown and described.
3. The design of the central raised polygonal figure h for the sides, door, and rear plate of a stove, as shown and described.
4. The ornamentation of the sides, rear plate, (being same as side plates,) door, and legs of a stove, with stars in relief, as shown and described.

FRANCIS H. ROOT.
